UNITED STATES PATENT OFFICE.

HUBERT K. KRANTZ, OF WILKINSBURG, PENNSYLVANIA, ASSIGNOR TO WESTINGHOUSE ELECTRIC & MANUFACTURING COMPANY, A CORPORATION OF PENNSYLVANIA.

ELECTRIC SWITCH.

Application filed August 8, 1922. Serial No. 580,409.

My invention relates to electric switches and particularly to those of the type wherein more than one switching operation is employed for starting motors.

5 My invention is particularly applicable for use in connection with small motors, such as are employed for driving household appliances and it has for one of its objects the provision of a compact structure embodying 10 switches for controlling the circuits through the starting and running windings of a motor, together with means for automatically interrupting the circuit through the motor in case a short circuit or an overload occurs— 15 either during the starting of the motor or when such motor is operating under running conditions.

Another object of my invention is the provision of means whereby the switch that 20 controls the circuit through the starting winding will be automatically moved to open position after sufficient time has elapsed to enable the motor to attain its normal running speed.

25 Another object of my invention is the provision of a simplified form of operating mechanism whereby but a single handle is necessary in order to manually effect the operation of both switches.

30 A further object of my invention is the provision of means whereby the position of the operating handle when at rest indicates the position occupied by the running switch.

Another object of my invention is the provision of an improved form of trip-free mechanism whereby the switch may be automatically disengaged from the closing mechanism, when the switch reaches its closed 40 position in order to insure that the switch will not be held closed against an overload on the circuit.

Still another object of my invention is to simplify and improve generally the construction and operation of circuit controlling devices of the character above referred to.

As shown in the accompanying drawings, 45 Figure 1 is a plan view of a switch embodying my invention, the cover and the handle being removed,

50 Fig. 2 is a view, partially in side elevation and partially in section, of the switch,

Fig. 3 is a detail view of the stationary contact members,

Fig. 4 is a plan view of the cover plate, 55

Figs. 5 and 6 are side elevational and plan views, respectively, of the handle bracket,

Figs. 7 and 8 are plan and side elevational views, respectively, of the bracket which carries the movable contact members 60 of the running switch,

Figs. 9 and 10 are plan and side elevational views, respectively, of the bracket which carries the movable contact members 65 of the starting switch,

Figs. 11 and 12 are plan and side elevational views, respectively, of the lever for locking the running switch,

Figs. 13 and 14 are detail views of the upper and lower bearings respectively for 70 the movable contact bracket members,

Figs. 15 is a detail view of one of the pins employed for effecting a connection between the handle bracket and the moving parts of 75 the switch,

Fig. 16 is a plan view showing the positions occupied by certain of the moving parts at one stage of their operation,

Fig. 17 is a diagrammatic view showing the relation of the switches with respect to 80 the circuits that are controlled thereby, and

Fig. 18 is a detail view, in perspective, of certain of the tripping mechanism which I employ.

The switch is provided with a cover 18 85 and a base 19. A frame 20 is secured to the base 19 by bolts 21. A bearing 23 is secured to the front of the frame 20 and is perforated to permit the passage therethrough of a handle shaft 24 that carries a 90 handle 25 which may be oscillated between stop members 26 and 27, the stop members consisting of bent-up portions of the frame 20. A rear bearing 28 is secured to the base 19 by upsetting the lower end at 29 (Fig. 2). The lower end of the shaft 24 is flattened 95 slightly so that the handle bracket 31 may be non-rotatably engaged thereby, by reason of the contour of a hole 32 in the bracket. (See Fig. 6.) The bracket 31 is of U-shape and is provided with a slot 33 at its middle portion within which a pin 34 may slide horizontally.

100 The pin 34 is provided with grooves 36

(Fig. 15) that are engaged by the ends of a pair of tension springs 37. The other ends of the springs 37 are supported by a pin 38, the upper and lower ends of which lie in the cut-out portions 39 (Fig. 9) of a carrier 41 for movable contact members 42 (only one of which is shown in Fig. 1) that co-operate with stationary contact members 43 to close the circuit through a starting winding of a motor connected in the circuit.

When the handle 25 is turned in a counter-clockwise direction, the pin 34, by reason of its location in the slot 33 of the handle bracket 31 will also be moved in a counter-clockwise direction and will engage with shoulders 44 (Figs. 1, 9 and 10) of the contact carrier 41, thus moving such contact carrier and the contact members that are carried thereby into engagement with the stationary contact members 43. This effects the closure of what I designate as the starting switch.

A tension spring 49 is supported at one of its ends by the pin 38, in a groove similar to the grooves 36 of the pin 34, and at its other end is supported by a pin 51 whose ends lie in recesses 52 of another movable contact bracket 53 (Figs. 1, 7 and 8) that serves as a support for movable contact members 54 that are moved into and out of engagement with stationary contact members 56 to effect a closure of what is herein designated as the running switch.

When the starting switch bracket 41 and the pin 38 that is supported thereby are turned in a counter-clockwise direction, the spring 49, which is under tension, is carried across the axis of the rotatable members, thereby changing the direction of tension exerted by such spring 49 upon the bracket 53 and causing such bracket to be moved to the position shown in Fig. 16. At this stage of the operation, the running and starting switches are both closed.

As the contact carrying brackets 53 and 41 move in clockwise and counter-clockwise directions, respectively, shouldered portions 57 of the bracket 53 engage the front and rear ends, respectively, of the pin 34, moving it radially out of engagement with the shouldered portion 44 of the bracket 41, thus disengaging such bracket and permitting it to move independently of the handle 25 and the handle bracket 31.

A relatively stiff spring 58 has one of its ends secured at the point 59 to the frame 20 and the other end thereof secured at 61 to the bracket 41 (see Figs. 1, 4 and 9). As the handle is turned to close the starting switch, the movement of the bracket 41 increases the tension of the spring 58. Upon the pin 34 being tripped free of the shoulder 44 of the bracket 41, as above described, the tension of the spring 58 is sufficient to return the bracket 41 to the position shown

in Fig. 1, against the tension of the springs 37 and 49. This movement also returns that portion of the spring 49 which is supported by the pin 38 to the position illustrated in Fig. 1.

A locking lever 62 is pivotally supported in the frame 20, by a pin 60, and is normally biased in a clockwise direction by the spring 63 (Figs. 1 and 2). A pin 64 extends through openings 65 in the lever 62 and carries rollers 66 at its front and rear ends. When the bracket 53 has been moved to the position shown in Fig. 16, the rollers 66, by reason of the clockwise tension exerted upon the lever 62 will engage a pair of shoulders 67 on the bracket 53 to hold the bracket 53 in closed position (as shown in Fig. 16) against the tension of the spring 49, when the end of that spring which is supported by the pin 38 has been returned to the position shown in Fig. 1, as above explained.

The return movement of the bracket 41, under the tension of the spring 58, places the handle bracket 31 under tension, by reason of the elongation of the springs 37, but the bracket 31 is prevented from moving to "off" position so long as the pin 34 remains in engagement with the shouldered portion 57 of the bracket 53. The position occupied by the handle 25, with respect to the stop lugs 26 and 27, thus indicates that the running switch is closed.

An electromagnet 68 for controlling the starting switch comprises two coils, 69 and 70, that may contain unequal ampere turns, and which are connected in the circuit, as shown in Fig. 17, to co-operate with an armature 71 which is carried upon a tail piece 72 of the starting switch bracket 41. The differential in the magnetic forces of the coils excited on the armature 71 is sufficient to hold the starting switch closed when the switches are in the position occupied in Fig. 16.

The effective holding force of the magnet 68 varies, as will be hereinafter explained, but normally holds the starting switch closed against the tension of the spring 58 for a short period. When the magnetism has been sufficiently reduced, as will be hereinafter explained, the tension of the spring 58 will impart an opening movement to the starting switch, as described above.

With the starting switch in the position illustrated in Fig. 1, and the running switch as illustrated in Fig. 16, the motor will operate under normal running conditions and may be stopped either by manually effecting an opening movement of the running switch or by automatically effecting such movement.

The running switch may be opened manually by turning the handle 25 in a clockwise direction, thus bringing the beveled portions 73 (Figs. 5 and 6) of the handle brack-

et 31 into engagement with the rollers 66 to cam them out of engagement with the shou-
dered portions 67 of the bracket 53. The
handle is then held in its "off" position
5 against the stop 26, by the tension of the
springs 37, and the running switch bracket
53 is snapped to its open position by the ten-
sion of the spring 49.

The running switch may be opened auto-
10 matically upon the occurrence of an over-
load by the coil 70 that actuates an arma-
ture 74 which is pivotally supported upon
the pin 60 and is biased outwardly by a
spring 63a. An abnormal energization of the
15 coil 70 will attract the armature 74 against
the tension of the spring 63a, and move it
into engagement with lugs 62a of the lever
62 and causes a counter clockwise movement
by the lever 62, thus moving the rollers 66
20 out of engagement with the shoulders 67 of
the running switch bracket and permitting
the spring 49 to return the running switch
bracket 53 to open position. The opening
movement of the bracket 53 causes the release
25 of the pin 34 from its engagement with the
shoulders 57 and allows the handle 25 to be
returned to its off position, as in the case of
the manual operation above described.

As shown more clearly in Fig. 4, the
30 frame 20 is provided with stop portions 76
for engaging the front ends of the pins 38
and 51 to limit their movements, the rear
ends of the pins engaging the end walls of
arcuate slots 76a in the base 19. The bear-
35 ings 23 and 28 and the handle shaft 24 are
of short length to permit movement of the
spring 49 across the axis of the movable
parts that are supported thereby, and the
bracket members 31, 41 and 53 are of U-
40 shape, to leave a clear space for movement
by the springs 37 and 49. Furthermore, this
U-shape construction of the bracket members
41 and 53, together with their recesses, which
radiate from their central portions (see Figs.
45 7 and 9) permits the ready assembly or dis-
assembly of these parts, in that such brackets
may be inserted into place from the side
of the switch by moving them radially into
engagement with the grooved portion of the
50 bearing members 23 and 28. The tension ex-
erted by the spring 49, through the pins 38
and 51, serves to hold the recessed central
portions of these brackets into close-fitting
engagement with the grooved bearing mem-
55 bers 23 and 28. The pins 34, 38 and 51 are
each grooved adjacent to their ends in sub-
stantially the manner indicated in Fig. 15,
so that such end grooves will engage their
respective associated brackets to prevent ver-
60 tical movement by the pins.

Referring now more particularly to Fig.
17, a main circuit 77 is controlled by the
running switch 79. The running switch 79
primarily controls the supply of current to
a starting winding 81 of a motor and a run-

ning winding 82 thereof, but only indirectly
controls the flow of current to the former
winding. When the running switch 79 is
closed, it completes the circuit through the
70 coil 70 and the winding 82. When starting,
the switch 42 is also closed, and the circuit
through the starting winding 81 is complete.

Upon the closure of both the starting
switch and the running switch, current is
supplied to both windings 81 and 82. The
75 differential magnetism of the coils 69 and
70 is then sufficient to maintain the arma-
tures 71 in the position illustrated in Fig. 16,
and a high temperature-coefficient resistance
84 is provided in the shunt circuit 78. After
80 current has been directed through the shunt
circuit and coil 69 for a short time, the re-
sistance offered by the element 84 increases
by reason of the heating thereof and causes
more current to flow through coil 70, thus
85 reducing the holding force exerted by the
magnet 68 and permitting the spring 58 to
move the starting switch 42 (bracket 41) to
open position, as above described. The start-
ing switch will, therefore, not be held closed
90 for a period sufficient to cause injury to the
motor that the apparatus is designed to con-
trol.

Fig. 18 shows, in detail, the relation of
the coils 69 and 70 to the armatures 71 and
74. When the starting switch is closed
95 and the armature 71 moved to the position
shown in Fig. 16, the running switch is
caused to close as above explained. The cir-
cuit through the coils 69 and 70 is then com-
plete, causing the armature 71 to be re-
tained in the said position until the re-
sistance 84 becomes heated and the flow of
100 current therethrough reduced. This causes
an increased flow of current through the
coil 70. The flow of current through the
coil 69 being reduced and that through coil
70 increased, and the coils being energized
in opposite directions, the differential there-
between that creates a magnetic flux through
105 the core during starting, is reduced a suffi-
cient amount to permit the spring 58 to
open the starting switch against the mag-
netic force exerted upon the armature 71.
The circuit through the coil 69 and the
110 starting winding 81 is then broken, leaving
only the coil 70 effective. The coil 70, be-
ing in series with the main winding 82, then
acts as an ordinary overload coil and, owing
115 to the remote position then occupied by the
armature 71, any magnetic force set up
around the core 86 will be exerted mainly
upon the armature 74 against the tension of
a spring 63a, thus moving the armature 74
120 against the latch lever 62a and the tension
of the spring 63 to free the running switch
(running switch 79—bracket 53) from the
lever 62 and permitting the switch to be
moved to open position by the tension spring
125 49, as above described.

I have, therefore, provided means for insuring that the running switch shall not be maintained in closed position so long as an overload obtains on the circuit.

5 While the device has been described in its application to an alternating current motor, of the induction type, it may be employed in connection with various other classes of apparatus wherein primary and secondary 10 circuit conditions exist.

I claim as my invention:

1. The combination with a starting winding and a running winding, of means for closing the circuit of the starting winding, 15 means for closing the circuit of the running winding, and means controlled by conditions in one circuit for effecting an opening of the starting winding circuit after the circuit of the running winding has been 20 closed.

2. The combination with a starting winding, and a running winding, of means for closing the circuit of the starting winding, means for closing the circuit of the running winding, and means controlled by conditions in one circuit for effecting an interruption of the starting winding circuit within a short time after it has been closed.

3. The combination with a main circuit 30 and a shunt circuit, of a switch for controlling the main circuit, a switch for controlling the shunt circuit, means for closing the second named switch, and means responsive to the current in the shunt circuit for normally causing an opening movement of the said second named switch after a short period of time following its closure.

4. The combination with a main circuit, and a shunt circuit, of a switch for controlling the main circuit, a switch for controlling the shunt circuit, a common means for closing the switches, and means responsive to the current in the shunt circuit for normally causing an opening movement of the second named switch after a short period of time following its closure.

5. The combination with a main circuit and a shunt circuit, of a switch for controlling the main circuit, a switch for controlling the shunt circuit, means for closing the switches, and means responsive to the current in the shunt circuit for normally causing an opening movement of the second named switch after a short period of time following the closure of the said switches.

6. The combination with a starting winding and a running winding, of a switch for controlling the circuit through the starting winding, means for closing the switch 60 against tension, means controlled by conditions in the circuit through such switch for holding it closed and means normally effective after a short period of time for rendering said holding means ineffective.

65 7. The combination with a starting wind-

ing and a running winding, of a switch for controlling the circuit through the starting winding, means for holding the switch closed and means controlled by conditions in the circuit through the switch and normally effective only after a time interval for rendering the said holding means ineffective.

8. The combination with a switch for controlling a shunt circuit and a switch for controlling a main circuit, of a common means for closing the switches, means for holding the switches closed, means governed by predetermined conditions in one of the circuits for releasing one of the switches, and means governed by other predetermined conditions in one of the circuits for releasing the other switch.

9. The combination with a starting switch and a running switch, of a lever manually operable to close the switches, means for disengaging the starting switch from the said lever, means for returning the starting switch to open position independently of the lever, means controlled by conditions in the circuit for effecting an opening movement of the running switch and means for automatically returning the said lever to its off position when the said running switch is opened.

10. The combination with a starting switch and a running switch, of a common means including a handle for effecting a substantially simultaneous closing movement thereof, means controlled by conditions in its circuit, for effecting an opening movement of the starting switch, means carried by the running switch for maintaining the handle in its closed position, means controlled by conditions in the circuit of the running switch for effecting an opening movement thereof, and means for returning the handle to its open position when the running switch has been opened.

11. The combination with a starting switch and a running switch, of a main spring, of a handle for closing the starting switch against the tension of the spring, a yielding connection between the handle and the starting switch, a yielding connection between the starting switch and the main switch, whereby the main switch is placed under tension to effect a closing movement thereof when the starting switch is closed, means for disengaging the handle from the starting switch when in its closed position to permit the main spring to return the starting switch to open position and to reverse the direction of tension upon the running switch, a latch for holding the running switch closed, and means controlled by conditions in the running switch circuit for tripping said latch.

12. The combination with a starting switch and a running switch, of a spring, a handle for closing the starting switch

against the tension of the spring, a yielding connection between the starting switch and the running switch, whereby the running switch is placed under tension to effect a closing movement thereof when the starting switch is closed, means for disengaging the handle from the starting switch when in closed position, to permit the spring to return the starting switch to open position and 10 to reverse the direction of tension upon the running switch, a latch for holding the running switch closed, means controlled by conditions in the circuit of the starting switch for holding it closed against the tension of 15 the said spring, and means controlled by conditions in the running switch circuit for tripping said latch.

13. The combination with a starting switch and a running switch, of a spring, a handle 20 for closing the starting switch against the tension of the spring, a yielding connection between the starting switch and the running switch, whereby the running switch is placed under tension to effect a closing movement thereof when the starting switch is closed, means for disengaging the handle from the starting switch when in closed position, to permit the spring to return the starting switch to open position and to reverse the direction of tension upon the running switch, a latch for holding the running switch closed, and means for either manually 25 or automatically tripping said latch.

14. The combination with a starting switch and a running switch, of a spring, a handle for closing the starting switch against the tension of the spring, a yielding connection between the handle and the starting switch, a yielding connection between the starting switch and the running switch, whereby the running switch is placed under tension to effect a closing movement thereof when the starting switch is closed, means for disengaging the handle from the starting switch when in closed position, to permit the spring to return the starting switch to open position and to reverse the direction of tension upon the running switch, a latch for holding the running switch 30 closed, and means controlled by conditions in the running switch circuit for tripping said latch, the first named yielding connection being placed under tension upon opening movement of the starting switch and serving to return the handle to off position when the running switch is opened.

15. The combination with a main switch, of an auxiliary switch connected in shunt relation to the circuit of the main switch, means for closing the switches, and means controlled by conditions in the shunt circuit for normally effecting an opening movement of the auxiliary switch within a relatively short time after the same has been closed.

16. The combination with a main switch, of an auxiliary switch connected in shunt relation to the circuit of the main switch, means for closing the switches, means controlled by conditions in the shunt circuit for normally effecting an opening movement of the auxiliary switch within a relatively short period after the same has been closed, and means controlled by conditions in the circuit of the main switch for effecting an opening movement thereof.

17. The combination with a starting switch and a running switch, of a spring for normally biasing the starting switch to open position, a handle for closing the starting switch against the tension of the said spring, a magnet in the circuit of the starting switch for holding it closed against the tension of the said spring, and a tension connection between the starting switch and the running switch whereby the running switch is biased toward the position occupied by the starting switch.

18. The combination with a starting switch and a running switch, of a spring for normally biasing the starting switch to open position, a handle for closing the starting switch against the tension of the said spring, a magnet in the circuit of the starting switch for holding it closed against the tension of the said spring, and a tension connection between the starting switch and the running switch whereby the running switch is biased toward the position occupied by the starting switch, a latch normally biased into engagement with the running switch to maintain it in closed position, and an electromagnet in the circuit of the running switch for tripping the latch upon the occurrence of an overload in the said circuit.

19. The combination with a starting switch and a running switch, of a spring for normally biasing the starting switch to open position, a handle for closing the starting switch against the tension of the said spring, a magnet in the circuit of the starting switch for holding it closed against the tension of the said spring, a tension connection between the starting switch and the running switch whereby the running switch is biased toward the position occupied by the starting switch, a latch normally biased into locking engagement with the running switch to hold it in closed position, manually operable means for tripping the latch, and means controlled by conditions in the circuit for automatically tripping said latch.

20. The combination with a starting switch and a running switch, of a handle for closing the switches, means controlled by conditions in the starting switch circuit for automatically effecting an opening movement thereof, and means for effecting an opening movement of the running switch when the handle is moved to off position.

21. The combination with a movable switch member, of an actuating member therefor, an electromagnetic device for holding the actuating member in advanced position, means co-operating with the electromagnet to control a movement of the said switch member, and means controlled by conditions in the circuit for rendering the electromagnet ineffective to hold the actuating member in advanced position. 5
22. The combination with a movable switch member, of an actuating member therefor, an armature connected to the actuating member, a latch for holding the movable switch member in advanced position, an armature for effecting the tripping of the said latch, an electromagnet for co-operating with the said armatures, and means controlled by conditions in the circuit for selectively directing magnetic flux from the said magnet through the said armatures. 15
23. The combination with a starting winding and a running winding, of means for closing the circuit of the starting winding, means for closing the circuit of the running winding, and means controlled by conditions in either circuit for effecting an opening of the starting winding circuit after the circuit of the running winding has been closed. 20
24. The combination with a starting winding and a running winding, of means for closing the circuit of the starting winding, means for closing the circuit of the running winding, and means controlled by conditions in both of the circuits for effecting an opening of the starting winding circuit after the circuit of the running winding has been closed. 25
25. The combination with a starting winding and a running winding, of means for closing the circuit of the running winding, and means controlled by conditions in either circuit for effecting an interruption of the starting winding circuit within a short time after it has been closed. 45
26. The combination with a starting winding and a running winding, of means for closing the circuit of the running winding, and means controlled by conditions in both circuits for effecting an interruption of the starting winding circuit within a short time after it has been closed. 50
27. The combination with a switch for controlling a shunt circuit and a switch for controlling a main circuit, of a common means for closing the switches, means for holding the switches closed, means governed by predetermined conditions in both circuits for releasing one of the switches, and means governed by other predetermined conditions 55
- in one of the circuits for releasing the other switch. 60
28. The combination with a switch for controlling a shunt circuit and a switch for controlling a main circuit, of a common means for closing the switches, means for holding the switches closed, means governed by predetermined conditions in either circuit for releasing one of the switches, and means governed by other predetermined conditions in one of the circuits for releasing the other switch. 65 70
29. The combination with a main switch, of an auxiliary switch connected in shunt relation to the circuit of the main switch, means for closing the switches, and means controlled by conditions in a circuit controlled by one of the switches for normally effecting an opening movement of the auxiliary switch within a relatively short time after the same has been closed. 75 80
30. The combination with a main circuit and a shunt circuit, a switch for the main circuit, and a switch for the shunt circuit, of a pair of parallel connected electromagnetic devices responsive to conditions in the circuits connected thereto, one of the said devices serving to control the main switch and the other serving to control the auxiliary switch. 85 90
31. The combination with a main circuit and a shunt circuit, a switch for the main circuit, and a switch for the shunt circuit, of an electromagnet for controlling the said switches and having two parallel connected coils, and means responsive to current conditions of the circuit including one of the coils for controlling the operation of the electromagnet. 95 100
32. The combination with a main circuit and a shunt circuit, a switch for the main circuit, and a switch for the shunt circuit, of an electromagnet for controlling the said switch and having two parallel connected coils, and means responsive to current conditions of the circuits including the coils for controlling the operation of the electromagnet. 105 110
33. The combination with a main circuit and a shunt circuit, a switch for the main circuit, and a switch for the shunt circuit, of an electromagnet for controlling the said switches and having two parallel connected coils and means responsive to current conditions of either circuit including the coils for controlling the operation of the electromagnet. 115 120

In testimony whereof, I have hereunto subscribed my name this 12th day of July 1922.

HUBERT K. KRANTZ.
